GOLF PUTTER

Karsten Solheim, 501 W. Wakonda Lane,
Phoenix, Ariz. 85023

Filed Nov. 4, 1974, Ser. No. 520,535

Term of patent 14 years

Int. Cl. D21—02

U.S. CL. D34—5 GC

FIG. 1 is a perspective view of a golf putter embodying my new design.

FIG. 2 is a front view in elevation of the head of the golf putter shown in FIG. 1.

FIG. 3 is a bottom view of the putter head shown in FIG. 2.

FIG. 4 is a top view of the putter head shown in FIG. 2.

FIG. 5 is a rear view in elevation of the putter head shown in FIG. 2.

FIG. 6 is an end view in elevation of the putter head shown in FIG. 2 as seen from the toe.

FIG. 7 is an end view in elevation of the putter head shown in FIG. 6 as seen from the heel.

FIG. 8 is a sectional view of the putter head shown in FIG. 2 taken along a line 8—8 shown in FIG. 5.

The dominant feature of my new design of a golf putter resides in its head having a sculptured cavity in the rear, i.e., behind the striking face, said cavity being formed in a substantially oval shape with a peripheral wall sub-

stantially normal to the striking face and a concavely curved surface between said peripheral wall and the rear surface of said club head along the lower (sole) and outer (toe) sides thereof as shown.

I claim:

The ornamental design for a golf putter, substantially as shown and described.
